Harvey J. Harwood

United States Patent Office.

HARVEY J. HARWOOD, OF UTICA, NEW YORK.

Letters Patent No. 65,668, dated June 11, 1867.

IMPROVEMENT IN WOOD-SCREWS.

The Schedule referred to in these Letters Patent and making part of the same.

TO ALL WHOM IT MAY CONCERN:

Be it known that I, HARVEY J. HARWOOD, of Utica, in the county of Oneida, and State of New York, have invented a new and useful Improvement in Wood-Screws; and I do hereby declare that the following is a full, clear, and exact description of the construction and operation thereof, reference being had to the annexed drawings, making a part of this specification, in which—

Figures 1 and 11 are longitudinal elevations of variations of single-threaded screws.

Figures 2 and 12 are end views of single-threaded screws shown in figs. 1 and 11.

Figures 3, 4, and 8 are longitudinal elevations of variations of double-threaded screws.

Figure 5 is an end view of the double-threaded screw shown in fig. 4.

Figures 6 and 9 are longitudinal elevations of variations of triple-threaded screws.

Figures 7 and 10 are end views of the triple-threaded screws shown in figs. 6 and 9.

It will be seen by referring to the drawings that the lips come to an edge, or nearly to an edge, and are formed so deep that all of the end of the screw is in a lip, as seen in the single-threaded screws, figs. 1, 2, 11, and 12, or into lips, as seen in the double and triple-threaded screws, figs. 3, 4, 5, 6, 7, 8, 9, and 10.

The nature of my invention consists in the form of the lip points on metallic screws made to enter wood.

To enable others skilled in the art to make and use my invention, I will proceed to describe its construction and operation.

The screws can be made of the metal and in the form desired by any of the well-known means now in use. I prefer to thread and point the screws by rolling the blanks between dies made for that purpose. The screws can be operated in the same manner as the gimlet-pointed screw, and those that have more than one thread are operated in proportionally greater rapidity. Heretofore screws have been made with the core and thread both tapering at the point of the screw, or without either core or thread tapering at the point end of the screw, as they were made before the gimlet point was invented, while in mine the core tapers at the point end of the screw, and terminates a little short of the end of the screw, while the diameters of the threads or lips forming the point are not varied much, if any, from the diameter of the rest of the screw. They readily enter wood and hold to the extreme point better than any other screw now in use. The point or lip or lips of these screws open the wood sufficiently for the rest of the thread on the screw to enter, and there is no farther displacement of the wood except such as is produced by the core upon the edge of the thread as it follows the point; therefore it is less liable to split the wood than other screws, and forms a better thread in the wood. The cutting or entering edges of these screws do not all assume the same form; some have a round or curved entering edge, figs. 5 and 10; on some the entering or cutting edge is nearly straight from the centre of the screw out; others have a hook-shaped entering or cutting edge, figs. 1, 2, and 6. The pitch is greater between the lip and the thread than between two contiguous threads.

What I claim as my invention, and desire to secure by Letters Patent, is—

1. Forming the end of the screw into a lip or lips, substantially as described.
2. Extending the lip or lips of the screw beyond the terminus of the core, substantially as described.
3. Retaining the full size of the screw at the point without continuing the core to the point.
4. Increasing the pitch between the lip and first thread, substantially as described.

HARVEY J. HARWOOD.
